PANEL MOUNTING FOR TUBING AND ACCESSORIES FOR ANALYSIS APPARATUS

Leonard T. Skeggs, Cleveland, Ohio, and Blanche R. Stuart, Rutherford, N.J., assignors to Technicon Instruments Corporation, Chauncey, N.Y., a corporation of New York

Filed May 24, 1962, Ser. No. 197,421.
14 Claims. (Cl. 23—253)

This invention relates to automatic analysis apparatus and, more particularly, to an accessory panel for use with such apparatus.

In analysis apparatus of the type shown in U.S. Patent No. 2,797,149, issued June 25, 1957, a sample liquid is transmitted through the apparatus in the form of a stream and is treated with various streams of processing fluids and reagents for treating the sample to determine the quantity of a constituent thereof. The nature and quantities of the processing fluids and reagents vary depending upon the particular quantitative analysis of the sample, so that in the use of the apparatus for various analyses, the apparatus must be provided with various accessories which must be arranged according to the procedure established by the particular analysis. This involves the provision and arrangement of various pump tubes, mixing coils, connecting tubes, and other accessories which involves considerable time and effort, especially when only one analysis apparatus is available for performing various analyses.

One object of the present invention is the provision of means which are to be used in conjunction with an analysis apparatus and which provide accessories arranged according to a preestablished procedure for a particular analysis to eliminate the time and effort heretofore required for arranging the apparatus for said particular analysis.

A further object is the provision of an accessory panel which can be readily mounted on the pump housing of the analysis apparatus and which carries the necessary accessories performing a particular analysis.

The above and other objects, features and advantages of the present invention will be more fully understood from the following description of the invention considered in connection with the accompanying illustrative drawings.

In the drawings:

FIG. 1 is a top plan view of the accessory panel mounted on a pump of an analysis apparatus;

FIG. 2 is a vertical sectional view taken on line 2—2 of FIG. 1;

FIG. 3 is a vertical sectional view, similar to FIG. 2, but illustrating the panel removed from the pump;

FIG. 4 is a perspective view of part of a mixing coil and its associated mounting clamp;

FIG. 5 is a vertical sectional view, on a larger scale, taken on line 5—5 of FIG. 1;

FIG. 6 is a horizontal sectional view, on a larger scale, taken on line 6—6 of FIG. 2;

FIG. 7 is a vertical sectional view, on a larger scale, taken on line 7—7 of FIG. 2;

FIG. 8 is a perspective view of part of the panel and part of a pump housing, illustrating the operational relation therebetween; and

FIG. 9 is a perspective view of a part of the accessory panel.

Referring now to the drawings in detail, the accessory panel comprises a plate 10 which is adapted to be removably mounted on the upper surface of the housing or frame 12 of a proportional pump 14 of an analysis system of the type described in the above mentioned U.S. Patent No. 2,797,149. The pump is preferably of the type

2

shown in U.S. Patent No. 2,935,028, issued May 3, 1960, and has a series of longitudinally spaced, transversely extending pressure rollers 16 which are carried by an endless chain conveyor 18 for compressing a series of resiliently flexible pump tubes 20 against the pump platen 22 to simultaneously collapse the pump tubes as the rollers move longitudinally thereof for propelling the fluids, in proportional amounts, through their respective pump tubes for the pumping operation.

10 The plate has an opening 24 having the configuration shown in FIG. 1 through which the aforementioned parts of the pump extend when the accessory panel is mounted on the housing of the pump, as best seen in FIG. 2. The side edges of the plate have downturned flanges 26 which are adapted to engage the upper marginal side edge portions of the housing of the pump and the plate can be provided with bayonet slots 28 for interengaging screws 30 provided in the top of the pump housing for releasably mounting the panel on the latter. One end of the plate has an upturned flange 32 which carries a tube connecting device 34 carrying nipples 36 to which tubes can be connected for introducing the sample and processing fluids into the analysis system.

As best seen in FIG. 6, the tube connecting device comprises a pair of spaced plates 38 which are operatively connected to each other by screws 40 and the inner plate 38a is suitably secured to flange 32. Each nipple 36 is connected to one end of a companion tube 42 and the opposite end of the tube extends through a hole 44 in plate 38b.

15 The hole has an enlarged bore 46 and the enlarged opposite end 48 of the tube fits in said bore. Plate 38a is constructed in the same manner as plate 38b and carries tube 42' in axial alignment with the companion tubes 42 and the enlarged resilient ends 48 of the tubes engage 20 each other by tightening screws 40, and provide a fluid tight connection between companion tubes 42 and 42'. While only two inlet nipples 36 have been shown, it will be understood that the number provided depends upon the particular analysis which is to be performed and the 25 required number of processing fluids and reagents which are necessary for said analysis.

In using the panel, nipples 36 which are carried by plate 38b preferably are first connected to tubing which supply the reagents from supply bottles and then plate 38b 30 is secured to plate 38a by screws 40 so that all reagent connections are simultaneously made. The sample can be supplied from a tube which need not pass through device 34 but can be conveniently secured to plate 10.

The outlet nipples 36' of tubes 42' are connected by 35 suitable tubing 50 to the companion pump tubes 20 for pumping of the sample and processing liquid or reagent from the inlet nipples 36 through the system, and in this regard it will be understood that the number of pump tubes provided depends upon the particular analysis which is to be performed. As here shown, a pump tube 52 (FIG. 1) is provided having its inlet end 54 exposed to air so that during the operation of the pump, air is transmitted through the pump tube and is introduced into the liquid stream flowing into the adjacent pump tube 56, at 40 the H-shaped fitting 58 to form a segmented stream comprising longitudinally spaced liquid segments separated from each other by an intervening gas segment, as described in the aforementioned U.S. Patent No. 2,797,149.

45 The segmented stream is joined to the other fluid stream flowing through pump tube 59 and tube 59a which can be the sample stream, at T-fitting 60 and the resulting stream is transmitted through tubing 61 to the inlet end of a horizontally mounted helical mixing coil 62. The outlet end of the mixing coil is connected to the inlet end of another mixing coil 64 and the outlet end of the latter mixing coil is connected to the inlet end of a third

mixing coil 66. The outlet end of said mixing coil 66 is connected to an outlet nipple 68 so that the treated liquid stream can be transmitted to an analyzer (not shown), for example a colorimeter, by suitable tubing which is connected to nipple 68. The nipple is supported in an upstanding flange 70 provided at the end of the plate. Obviously, the number of mixing coils provided and the length of the mixing coils depend upon the particular analysis and it will be understood that the accessory panel will be provided with the proper mixing coils and other accessories in accordance with the analysis which is to be performed.

As best seen in FIGS. 1 and 4, the coils are removably mounted in open-top spring clamps 72 which resiliently grasp the outer surface of the coil. The clamps are 15 suitably connected to the top surface of plate 10. The various tubes are preferably secured to the top of the plate by clamps 74 to prevent extensive movement of the tubes.

As best seen in FIGS. 1, 5 and 9, a tube clamp 76 extends vertically upwardly from the top surface of plate 10 and has an upwardly inclined tube bearing surface 78 against which the fitting 58 and tube 59a are clamped by clamping plate 80 which is operated by clamping screws 82. The clamp has a cutout 84 so that when a 25 large number of pump tubes are needed for a particular analysis, the pump tubes can be spaced vertically from each other to limit the horizontal space which they might otherwise occupy on the plate. More specifically, certain of the tubes can be clamped by plate 80 while the 30 remaining pump tubes can extend through cutout 84. Moreover, by raising the level of certain of the tubes, more space is made available for the T-fitting 60 which need not lie horizontally but can be positioned vertically or inclined from the vertical. As herein shown, the cutout is not being utilized since the invention is illustrated with a small number of pump tubes.

A pair of longitudinally spaced tube holding members 86a and 86b are provided at the inlet and outlet ends, respectively, of the pump tubes 20. Each holding member is provided with a series of open top longitudinally extending laterally spaced grooves 88 in which the corresponding ends of the pump tubes extend. The sides of the holding members are provided with holes 90 and the platen 22 of the pump carries upstanding pins 92 which are adapted to extend into the holes when the panel is mounted on the pump housing, whereby the tube holding means and the pump tubes are properly positioned with respect to the platen and the tube compressing rollers 16 50 for the pumping operation.

To mount the accessory panel on the pump housing, the pump is moved into inoperative position by grasping handle 94 and lifting the tube compressing mechanism about its hinge pin 96. The panel is then placed on top of the pump housing so the pump tubes 20 overlie the platen 22 of the pump and the compressing rollers 16 are above the pump tubes. The tube holding members 86a and 86b are then mounted on pins 90 and the tube compressing means of the pump is moved into closed position so that the rollers engage the pump tubes. The inlet 60 nipples 36 and the outlet nipple 68 are then connected to the corresponding inlet and outlet tubes for the transmission of the sample and various processing liquids and reagents to the accessories on the plate 10 for treatment of the sample for analysis.

Preferably the panel 10 is made of a suitable transparent plastic material and the screws 30 and bayonet slots 28 need not be provided since the flanges 26 grasp the upper marginal side edge portions with enough force to prevent longitudinally sliding movement of the panel on the pump housing. The longitudinally correct positioning of the panel is easily determined since the panel is longitudinally positioned so that the holes 90 in the pump tube holders 86a and 86b overlie the pins 92 of the pump. A sheet of a suitable material is preferably 75

cemented to the bottom surface of the panel and has indicia 94 on its upper surface, such as writing, diagrams, identification, etc., which is visible through the transparent panel and identifies the various accessories and indicates the operational relationship therebetween.

While we have shown and described the preferred embodiment of our invention, it will be understood that the invention may be embodied otherwise than as herein specifically illustrated or described, and that certain changes in the form and arrangement of parts and in the specific manner of practicing the invention may be made without departing from the underlying idea or principles of this invention within the scope of the appended claims.

What is claimed is:

1. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) said plate having an opening therein through which said tube compressing means of said pump extends in the mounted condition of said panel on said pump, and
- (d) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel.

2. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) said accessories including means for mixing said sample with at least one of said processing fluids,
- (d) said plate having an opening therein through which said tube compressing means of said pump extends in the mounted condition of said panel on said pump, and
- (e) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel.

3. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through which a liquid sample stream and various fluid

- streams flow for processing said sample for analysis by said fluids,
- (b) said accessories being in fluid flow communication with each other in accordance with a predetermined arrangement so that said sample is processed by said fluids according to a pre-established procedure.
- (c) said accessories including means for introducing an inert gaseous fluid into said sample liquid stream to divide the latter into a series of longitudinally spaced liquid segments separated from each other by an intervening segment of said inert gaseous fluid,
- (d) said plate having an opening therein through which said tube compressing means extends in the mounted condition of said panel on said pump, and
- (e) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel.
4. Apparatus for an analysis system, comprising a pump, an accessory panel removably mounted on said pump, said pump having tube compressing means for compressing resiliently flexible pump tubes for pumping fluids through said tubes, respectively, said panel comprising:
- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) said accessories including means for mixing said sample with at least one of said processing fluids,
- (d) means for introducing an inert gaseous fluid into said sample liquid stream to divide the latter into a series of longitudinally spaced liquid segments separated from each other by an intervening segment of said inert gaseous fluid,
- (e) said plate having an opening therein through which said tube compressing means extends in the mounted condition of said panel on said pump, and
- (f) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel.
5. Apparatus for an analysis system, comprising a pump, an accessory panel removably mounted on said pump, said pump having tube compressing means for compressing resiliently flexible pump tubes for pumping fluids through said tubes, respectively, said panel comprising:
- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) tube connecting means positioned at each end of said plate for the transmission of fluids to and from said panel,
- (d) said plate having an opening therein through which said tube compressing means extends in the mounted condition of said panel on said pump, and
- (e) said plate carrying a series of resiliently flexible

- pump tubes for said fluids and for the sample connected to said accessories in fluid flow communication therewith in accordance with said predetermined arrangement and positioned above and extending across said opening for engagement by said tube compressing means for the pumping operation in said mounted condition of the panel.
6. Apparatus for an analysis system, comprising a pump, an accessory panel removably mounted on said pump, said pump having tube compressing means for compressing resiliently flexible pump tubes for pumping fluids through said tubes, respectively, said panel comprising:
- (a) a plate carrying a series of accessories through which a sample stream and various fluid stream flow for processing said sample for analysis by said fluids,
- (b) said accessories being in fluid flow communication with each other in accordance with a pre-determined arrangement so that said sample is processed by said fluids according to a pre-established procedure,
- (c) tube connecting means positioned at each end of said plate for the transmission of fluids to and from said panel,
- (d) said accessories including means for mixing said sample with at least one of said processing fluids, and
- (e) means for introducing an inert gaseous fluid into said sample liquid stream to divide the latter into a series of longitudinally spaced liquid segments separated from each other by an intervening segment of said inert gaseous fluid,
- (f) said plate having an opening therein through which said tube compressing means extends in the mounted condition of said panel on said pump, and
- (g) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel.
7. Apparatus for an analysis system, comprising a pump, an accessory panel removably mounted on said pump, said pump having tube compressing means for compressing resiliently flexible pump tubes for pumping fluids through said tubes, respectively, said panel comprising:
- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) said plate having an opening therein through which said tube compressing means extends in the mounted condition of said panel on said pump,
- (d) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel, and
- (e) tube holding means carried by said panel and spaced from each other longitudinally of said tubes for holding said tubes in side-by-side relation with said tubes extending longitudinally between said tube holding means.

8. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) said plate having an opening therein through which said tube compressing means extends in the mounted condition of said panel on said pump, and
- (d) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel,
- (e) said plate having indicia identifying said accessories and indicating the interconnection of said accessories with each other.

9. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) tube connecting means positioned at each end of said plate for the transmission of fluids to and from said panel,
- (d) said accessories including means for mixing said sample with at least one of said processing fluids,
- (e) means for introducing an inert gaseous fluid into said sample liquid stream to divide the latter into a series of longitudinally spaced liquid segments separated from each other by an intervening segment of said inert gaseous fluid,
- (f) said plate having an opening therein through which said tube compressing means extends in the mounted condition of said panel on said pump,
- (g) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel, and
- (h) tube holding means spaced from each other longitudinally of said tubes for holding said tubes in side-by-side relation with said tubes extending longitudinally between said tube holding means.

10. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through

which a sample stream and various fluid streams flow for processing said sample for analysis by said fluids,

- (b) said accessories being in fluid flow communication with each other in accordance with a predetermined arrangement so that said sample is processed by said fluids according to a pre-established procedure,
- (c) said plate having an opening therein through which said tube compressing means extends in the mounted condition of said panel on said pump,
- (d) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel, and
- (e) means positioned at the outlet end of said pump tubes for holding said tubes in vertically spaced relation to reduce the horizontal space that would be normally occupied by said tubes.

11. Apparatus for an analysis system, comprising a pump, an accessory panel removably mounted on said pump, said pump having tube compressing means for compressing resiliently flexible pump tubes for pumping fluids through said tubes, respectively, said panel comprising:

- (a) a plate carrying a series of accessories through which a sample stream and various fluid streams flow for processing said sample for analysis by said fluids,
- (b) said accessories being in fluid flow communication with each other in accordance with a predetermined arrangement so that said sample is processed by said fluids according to a pre-established procedure,
- (c) tube connecting means carried by said plate for the transmission of fluids to and from said panel,
- (d) said accessories including means for mixing said sample with at least one of said processing fluids,
- (e) means for introducing an inert gaseous fluid into said sample liquid stream to divide the latter in a series of longitudinally spaced liquid segments separated from each other by an intervening segment of said inert gaseous fluid,
- (f) said plate having an opening therein through which said tube compressing means extends in the mounted condition of said panel on said pump,
- (g) said plate carrying a series of resiliently flexible pump tubes for said fluids and for the sample connected to said accessories in fluid flow communication therewith in accordance with said predetermined arrangement and positioned above and extending across said opening for engagement by said tube compressing means for the pumping operation in said mounted condition of the panel, and
- (h) tube holding means longitudinally spaced from each other for holding said tubes in side-by-side relation with said tubes extending longitudinally between said tube holding means,
- (i) said plate having indicia identifying said accessories and indicating the interconnection of said accessories with each other.

12. Apparatus for an analysis system, comprising:

- (a) a pump having a frame and tube compressing means for compressing a plurality of resiliently flexible pump tubes for pumping a sample stream and a processing fluid stream through said system for treatment of said sample by said processing fluid, and
- (b) a panel mounted on said frame and having an opening in registry with said tube compressing means,
- (c) said panel having a series of pump tubes positioned over and extending across said opening for engage-

ment by said tube compressing means for the pumping of said sample and said processing fluid, and
(d) means on said panel in fluid flow communication with said pump tubes for treatment of said sample by said processing fluid.

13. Apparatus for an analysis system, comprising:

- (a) a pump having a frame and tube compressing means for compressing a plurality of resiliently flexible pump tubes for pumping a sample stream and a processing fluid stream through said system for treatment of said sample by said processing fluid, and
- (b) a panel mounted on said frame and having an opening in registry with said tube compressing means,
- (c) said panel having a series of pump tubes extending longitudinally across said opening for engagement by said tube compressing means for the pumping of said sample and processing fluid, and
- (d) means on said panel in fluid flow communication with said pump tubes for treatment of said sample by said processing fluid,
- (e) said last mentioned means including mixing means for mixing said sample with said processing fluid.

14. Apparatus for an analysis system, comprising a pump, an accessory panel removably mounted on said pump, said panel comprising:

- (a) a plate carrying a series of accessories through

5

10
15

which a sample stream and various fluid streams flow for processing said sample for analysis by said fluids,

- (b) said accessories being in fluid flow communication with each other in accordance with a predetermined arrangement so that said sample is processed by said fluids according to a pre-established procedure,
- (c) said plate carrying a series of resiliently flexible pump tubes for said fluids and for the sample connected to said accessories in fluid flow communication therewith in accordance with said predetermined arrangement for the pumping of said fluids and samples, and
- (d) tube connecting means positioned on said plate for the transmission of fluids to and from said panel, said tube connecting means being spaced from each other longitudinally of said tubes, said plate having an opening between said tube connecting means providing access of tube compressing means to said tubes for the pumping operation.
